DESIGN FOR A PARKING METER

Marcus H. Rhodes, Hartford, Conn., assignor to
M. H. Rhodes, Inc., Hartford, Conn., a corpora-
tion of Delaware

Application September 28, 1938, Serial No. 80,123

Term of patents 3½ years

To all whom it may concern:

Be it known that I, Marcus H. Rhodes, a citizen of the United States and a resident of Hartford, Hartford County, Connecticut, have invented a new, original, and ornamental Design for a Parking Meter, of which the following is a specification, reference being had to the accompanying drawing, forming part thereof, in which

Fig. 1 is a front elevation of a parking meter embodying my new design;

Fig. 2 is a right side elevation of Fig. 1;
Fig. 3 is a rear elevation, viewed from the right
side of Fig. 2; and,
Fig. 4 is a top plan view of Fig. 3.

I claim:
The ornamental design for a parking meter,
substantially as shown.

MARCUS H. RHODES.
